WINDOW GUARD

Simon Dorf, Brooklyn, N. Y.

Application April 6, 1937, Serial No. 135,250

5 Claims. (Cl. 20--79)

This invention relates to window guards.

An object of this invention is to provide an extremely simple window guard comprising a pair of interpivoted bars, the ends of which may be inserted in the grooves at the sides of the window frame, the construction being such that downward pressure on the guard when installed, will serve to tighten the guard in the frame to prevent accidental loosening.

10 It is a further object of this invention to provide in a window guard of the character described, means to prevent the guard from being accidentally removed from or falling out of the frame, said means further serving to cut down 15 the spaces between the guard, the window frame and the sash, providing an additional safeguard to prevent children or objects from falling through the guard.

Another object of this invention is to provide 20 a strong, compact and rugged window guard of the character described which may be collapsed into a compact package, which is easy to install or remove, which shall be relatively inexpensive to manufacture, and, withal, practical and efficient 25 to a high degree in use.

Other objects of this invention will in part be obvious and in part hereinafter pointed out.

The invention accordingly consists in the features of construction, combinations of elements, 30 and arrangement of parts which will be exemplified in the construction hereinafter described, and of which the scope of application will be indicated in the following claims.

In the accompanying drawing, in which is 35 shown one of the various possible illustrative embodiments of this invention,

Fig. 1 is a front elevational view of a window frame, provided with window sashes and a guard embodying the invention;

40 Fig. 2 is a cross-sectional view taken on line 2-2 of Fig. 1;

Fig. 3 is a cross-sectional view taken on line 3-3 of Fig. 1;

45 Fig. 4 is a side-elevational view of the guard in collapsed condition, with the rope removed; and

Fig. 5 is a front elevational view of part of a frame, and window guard embodying a modified construction.

50 Referring now in detail to the drawing, 10 designates a window frame in which are slidably mounted a front window sash 11, a rear window sash 12, and which is provided with a window guard 14 embodying the invention. The frame 55 may be of usual construction and the side por-

tions thereof are provided with front and rear parallel spaced grooves 15 and 16, in which the window sashes 11 and 12 are slidably mounted. Between the grooves 15 and 16 are furring strips 17. At the outer sides of the grooves 16 are furring strips 17a.

The window guard 14 comprises a pair of elongated bars 18 and 19 of substantially the same length. These bars may be made of wood or any other suitable material and are preferably of 10 substantially square or rectangular cross section. The bars are interpivoted at substantially the mid portions thereof by means of a bolt 20 passing through openings in said bars. When the guard is collapsed, the bars lie alongside one another 15 having inner adjacent surfaces 18a, 19a. The bar 18 may be provided with a countersunk 21 for receiving the head of the bolt. The bars 18 and 19 are preferably of similar cross section. The width of each bar is preferably more than 20 half the width of the groove 16 whereby the combined width of the bars is greater than the width of the groove. The outer ends of the bar 18 are preferably formed with notches 22 and 23 at 25 the outer side or surface 18b thereof, leaving narrowed end portions 22a and 23a at the outer ends of said bar. The depth of the notches 22 is equal to the difference between the width of the groove 16 and the combined widths of the bars 18, 19.

The manner of installing the window guard will 30 now be described. When the window guard is collapsed, the bars 18 and 19 are co-extensive and superimposed one on the other. The inner face 18a at the bar 18 facing the inner surface 19a of the bar 19. The bars may then be swung open 35 about the bolt 20 and the lower ends of the bars inserted at the bottom of the grooves 16 in contact with the bottom portion 10a of the window frame. The lower end 25 of the bar 19 is placed in contact with the furring strip 17a at the outer 40 side of one groove 16. The narrowed portion 23a at the lower end of the bar 18 is contacted with the furring strip 17 at the inner side of the other groove 16, and likewise in contact with the bottom portion 10a of the window frame.

45 The upper end 28 of the bar 18 extends within said other groove 16 and in contact with the furring strip 17a. The upper narrowed end 22a of the bar 18 is received in the first groove 16 and in contact with the furring strip 17. It will 50 thus be noted that with such construction the bars need not be forced into the grooves, as movement of the bars in their own planes about the pivot bolt 20 will move the outer ends of the bars into the grooves 16 at top and bottom. The 55

furring strips 17 engage within the notches at opposite ends of bar 18.

The narrowed end 22a of the bar 18 may be provided with a bevelled surface 22b to contact the inner surface of the groove 16. The outer end of the bar 19 may also be bevelled as at 29a to contact the inner surface of the other groove 16.

It will now be noted that when the window guard is mounted within the window frame, there will be no looseness sideways, as one bar contacts the furring strip 17 and the other bar contacts the furring strips 17a. Furthermore, should a weight be imposed downwardly, on the guard, the guard will become tighter wedged within the grooves of the window frame.

Means is provided for retaining the guard within the frame against accidental removal. To this end the bar 18 is provided with a pair of hooks 30 and 31 screwed into opposite side surfaces 18c and 18d thereof and spaced on opposite sides of the bolt 20. There is also attached to the bar 19 a pair of hooks 32 and 33 screwed to the opposite side surfaces 19c and 19d thereof. A rope or tie cord of any suitable construction, designated by numeral 35 in the drawing, may be tied to the bar 19 above the hook 33, then looped about the bar 18 above the hook 31, then brought down and looped about the bar 19 below the hook 32 and then looped about the bar 18 below the hook 30 and then brought up and looped about the bar 19 above the hook 33 and tied thereto. The rope 35 will thus have two parallel horizontal portions 35a and 35b and two vertical portions 35c and 35d. These portions traverse the triangular spaces between the bars and the sides of the frame and the window sash 12 above the guard, thus serving as an additional safeguard to prevent objects or persons, for example, children, from falling through the window guard. Furthermore, the rope prevents any pivotal movement of the bars about the bolt 20 and hence prevents accidental displacement or removal of the guard from the frame. Obviously the rope may be tied to the bars in any suitable manner, either being threaded through the hooks, or wound about the hooks.

It will be observed that with the construction described hereinabove, the front window sash 11 may be moved up and down to any desired position. If desired, furthermore, the window guard may be placed within the grooves 15 to permit up and down movement of the window sash 12.

In Fig. 5 there is shown a window guard 14a similar to the window guard 14, except that the bars 50 and 51 are of unequal length. With such construction the upper end 51a of one bar may be located below the upper end 50a of the other bar. Thus, should a person desire to work at the window, for example, in hanging clothes on the line, at the left side of the window, the fact that one bar of the guard is lower than the other facilitates hanging of the clothes at the left side of the window. Furthermore, the bars 50 and 51 are shown to have through openings 52, through which the rope 35 passes. The rope may be threaded through the openings 52 and tied to hold the window bars against pivotal movement and to prevent removal thereof through the window. Obviously, if it is desired to remove the guards 14 and 14a from the window, it is merely necessary to untie the cord.

Hooks may be affixed to the ends of the bars, for engagement with the frame, so that the guard may be mounted on the outside or inside of the frame, instead of within the grooves.

The upper half of either one or the other of the

bars may be omitted to give room for hanging out clothes, in which event a single flexible member may interconnect the bars to prevent them from opening up.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A window guard comprising a pair of elongated bars of substantially equal length and of rectangular cross section and having superimposed adjacent surfaces, a bolt passing through said bars at substantially the mid points thereof for pivotally connecting said bars together, said bars being adapted to be pivotally moved, one relative to the other, about said bolt to intersecting position, a pair of members attached to each bar on opposite sides of said bolt, and a flexible cord engaging said members on said bars to prevent relative pivotal movement of said bars.

2. In combination with a window frame having aligned, vertical grooves in the opposite sides thereof, a window guard for said frame comprising a pair of elongated bars pivoted together at intermediate portions thereof, the outer ends of said bars being received within said grooves, the ends of one of said bars contacting the furring strips at the inner sides of said grooves, and the ends of the other bar contacting the furring strips on the outer sides of said grooves, and a flexible cord tied to said bars on opposite sides of said bolt and traversing the triangular spaces between said bars, the frame and the window sash within said groove.

3. In combination, a window frame having vertical, aligned grooves in the opposite side portions thereof and being provided with furring strips on the inner and outer sides of said grooves, a window guard for said frame comprising a pair of elongated bars of substantially similar length pivoted together substantially at the mid portions thereof, said bars being of rectangular cross section and adapted to be moved into co-extensive position to bring adjacent faces of said bars into superimposing position, the lower ends of said bars being received within the lower ends of said grooves and contacting the bottom of said frame, the upper ends of said bars being received within said grooves at points above the bottom of the frame, the outer ends of one of said bars contacting the inner furring strips of said grooves, the outer ends of said other bar contacting the outer furring strips of said grooves, the combined width of said bars being greater than the width of said grooves, and the outer ends of one of said bars being notched to provide narrow portions at the end of said bar, and the inner furring strips being received within said notches, and a rope tied to portions of said bars on opposite sides of said bolt and having a pair of parallel horizontal portions and a pair of parallel vertical portions.

4. A window guard comprising a pair of elongated, straight bars pivoted together at substantially the mid portions thereof, and flexible non-stretchable means interconnecting said bars to

limit relative pivotal movement of one with respect to the other.

5. In combination with a window frame having grooves in the side portions thereof, a window guard for said frame comprising a pair of bars pivoted together at intermediate portions, the ends of said bars projecting into said grooves and being otherwise unattached to said frame, whereby said guard may be removed from said frame by pivotally moving said bars one relative to the other to withdraw the ends of said bars

from said grooves, and means carried wholly by said bars to prevent relative pivotal movement between said bars, whereby to retain said window guard within said frame, said means comprising a flexible cord interconnecting portions of one of said bars on opposite sides of the pivot connection between said bars, to portions of the other of said bars on opposite sides of said pivot connection.
